UNITED STATES PATENT OFFICE.

JOHN MACGREGOR, OF NEEDHAM, MASSACHUSETTS, ASSIGNOR OF ONE-HALF TO DR. SANNO & HOSKINS, INC., A CORPORATION OF PENNSYLVANIA.

GUARD FOR HYPODERMIC NEEDLES.

Application filed March 8, 1921. Serial No. 450,663.

The object of my invention is to provide a suitable protection for a hypodermic needle during the process of sterilization separately or with other instruments and at other times, if so desired, whereby danger of injury to the needle either by dulling of its point or bending the needle is guarded against.

In general construction, my invention consists in providing the needle hub in which the needle is fitted with a guard which may be placed over the needle and detachably secured to the hub, the length of the guard being sufficient to extend beyond the point of the needle and thereby prevent the same coming in contact with the sterilizing vessel or any other object which might cause injury to the needle.

In the preferred form of my improvement, the hub is provided with a threaded portion upon which is screwed the tubular protecting guard, and desirably, the screw joint is made left handed so that with the hub attached to the syringe with a right handed screw thread, the removing of the guard would tend to tighten the hub in position on the syringe rather than loosen it.

With the above and other objects in view, the nature of which will be more fully understood from the description hereinafter, the invention consists in the novel construction of guards for hypodermic needles, as hereinafter more fully described and defined in the claims.

Referring to the drawings; Fig. 1 illustrates the end of a syringe with a hypodermic needle attached and with the guard unscrewed and in the act of being removed; Fig. 2 is a sectional view of the hypodermic needle with the guard removed and with the usual fine wire inserted through the needle for insuring the aperture therein remaining clear; Fig. 3 is a side view of the needle hub and needle, as shown in Fig. 2, but with the needle guard screwed in position, the latter being shown in section; and Fig. 4 is a sectional view illustrating a vessel containing sterilizing fluid and in which the hypodermic needle protected by its guard is placed during the process of sterilizing.

5 5 represents the end of a hypodermic syringe and is provided with a nozzle 6 having a right handed screw thread 7 thereon. 8 represents a needle hub having a screw threaded socket 9 adapted to screw tightly upon the nozzle end 6 of the syringe.

The needle hub 8 is provided with an extended nipple 10 of relatively small diameter through which the hypodermic needle 14 extends and in which it may be attached in any suitable manner. This nipple 10 is provided near its base with a screw thread 11 preferably of the left hand character. 12 represents a fine wire which is temporarily inserted through the tubular aperture of the needle, but which is removed when the needle is applied to the syringe. 13 represents a guard of cylindrical cross section and tubular in shape and is internally screw threaded at one end to screw upon the left hand thread 11 of the nipple forming a part 70 of the hub 8. This guard 13 is of a length somewhat greater than the needle 14 and preferably greater than the end of the projecting part of the wire 12, so that when it is in position, as indicated in Fig. 3, it may 75 not only act as a guard to the needle itself, but also to the wire 12, if the same happens to be employed.

When it is desired to sterilize the hypodermic needle, the guard 13 is screwed upon 80 the nipple 10 and the hub and its needle with the guard attached may be detached from the syringe body and these parts may then be placed in the sterilizing vessel 15 containing the sterilizing fluid 16, as indicated in Fig. 4. During this operation of sterilizing (which may include boiling) the wire 12 may be inserted or omitted, but preferably omitted, so as to leave the canula of 85 the needle free for the entrance of the sterilizing fluid. It will be seen that the guard 13 being open at the bottom permits the free access of the sterilizing fluid to the needle, and this may be facilitated by providing, if desired, one or more perforations 17 in the 90 side wall of the guard. The guard permits the boiling fluid to completely surround the needle and to circulate through the canula thereof as well as outside, and sterilize the needle thoroughly. Even if the needle be 95 put into the sterilizer with many other instruments (one of which is shown in Fig. 4) instead of making a separate treatment of the needle by itself, the risk of injury to the needle from other instruments in the 100 sterilizer is completely avoided.

Aside from the use of my improved guard for the more important sterilizing operation, it may be employed as part of the syringe equipment to protect the needle when 110

not in use. While I have shown the guard as detachably secured to the nipple of the hub by means of a screw threaded joint, it is manifest that the attachment may be made in any other manner, such as a slip joint having sufficient friction, a bayonet joint or other convenient mode of application, though I prefer the screw threaded joint, as described.

I do not restrict myself to any special manner of attaching the hub to the nozzle of the syringe, but prefer a screw threaded connection as shown. While the special function of the guard is to protect or shield the needle during sterilization, nevertheless there is an additional advantage obtained, namely, that of providing the physician with an absolutely sterile needle at the time of use for injection. After the hub, needle and guard, with or without the syringe proper, have been sterilized as a complete unit, the guard may be removed by a twist of the fingers and the injection may be made without the needle itself being touched with the fingers.

In some cases the needle may be attached to the syringe in some other manner, such as by being fitted directly to the nozzle end and in such case, the guard would be detachably secured to the nozzle itself, which would be substantially equivalent to having the needle hub 8 as an integral or fixed part of the syringe body.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a device of the character stated, a hypodermic needle and hub in which it is held and whereby it may be detached from a syringe body, the hub provided with a tapered nipple through which the needle extends and said nipple screw threaded only adjacent to its base close to the hub part, combined with a tubular guard normally open on its end and detachably secured to the threaded nipple of the hub by being screwed thereon and also having a length whereby it extends at all times beyond the

point of the needle, said guard having a smooth interior diameter considerably larger than the diameter of the needle and the tapered nipple so that the disinfectant fluid may contact with both the needle and tapered nipple, the construction being such that the hub associated with the needle and guard may be detached from the syringe body when they are to be placed in an antiseptic fluid or when being stored.

2. In a device of the character stated, a hypodermic needle and a hub in which it is held and whereby it may be detached from a syringe body, said hub screw threaded on its inside for attachment to said syringe body and provided with a tapered nipple through which the needle extends and said nipple screw threaded on its outer surface adjacent to the hub part, one of said screw threads being right handed and the other left handed, combined with a tubular guard normally open on its end and detachably secured to the nipple of the hub by being screwed thereon, said guard extending beyond the point of the needle and considerably larger than the diameter of the needle and tapered nipple beyond the screw thread thereof so that the disinfectant fluid may contact with both the needle and the tapered nipple, the construction being such that the hub associated with the needle and guard may be detached from the syringe body when they are placed in an antiseptic fluid and whereby the guard is detachable from the nipple and may be unscrewed from the nipple without loosening the hub upon the syringe body.

3. In a hypodermic syringe, a body, a needle, and means comprising a hub having a screw threaded nipple for holding the needle in position upon the syringe body, combined with a detachable hollow guard of greater length than the combined length of the nipple and exposed needle, said guard detachably secured to the threaded nipple and providing a hollow chamber open at its end beyond the needle and into which chamber the needle extends, and whereby further, both the needle and the nipple supporting it may be fully shielded and at the same time freely subjected to a sterilizing fluid passing into the chamber of the guard while it protects the needle against injury, said guard being detachable to expose the sterilized needle for immediate use by the physician without touching it with the fingers.

In testimony of which invention, I hereunto set my hand.

JOHN MACGREGOR.
